UNITED STATES PATENT OFFICE.

EDWARD B. JONES, OF SPRINGFIELD, ILLINOIS.

DESIGN FOR A RAILWAY-COACH BODY.

47,791.

Specification for Design.

Patented Sept. 7, 1915.

Application filed July 13, 1914. Serial No. 850,827. Term of patent 3½ years.

To all whom it may concern:

Be it known that I, EDWARD B. JONES, a citizen of the United States, residing at Springfield, in the county of Sangamon and State of Illinois, have invented a new and original Design for Railway-Coach Bodies, of which the following is a specification, reference being had to the accompanying drawing, forming part thereof.

The drawing is a side elevation of a railway coach, illustrating my new design.

I claim:—

The ornamental design for a railway coach body, as shown.

EDWARD B. JONES.
